Primary Examiner—Robin V. Taylor*Attorney, Agent, or Firm*—Kelly Bauersfeld Lowry & Kelley, LLP.[57] **CLAIM**

The ornamental design for a hose end trigger multi-pattern spray nozzle, as shown and described.

DESCRIPTION

FIG. 1 is a side elevational view of a hose end trigger multi-pattern spray nozzle embodying my new design, it being understood that the opposite end is a mirror image thereof;

FIG. 2 is a front elevational view thereof;

FIG. 3 is a rear elevational view thereof;

FIG. 4 is a top plan view thereof; and,

FIG. 5 is a bottom plan view thereof.
